UNITED STATES PATENT OFFICE.

ANTHONY P. LIEDER AND JOSEPH F. SMITH, OF JACKSON, MICHIGAN.

GREASE CUP.

Application filed May 5, 1921. Serial No. 467,047.

To all whom it may concern:

Be it known that we, ANTHONY P. LIEDER and JOSEPH F. SMITH, citizens of the United States, residing at Jackson, in the county 5 of Jackson and State of Michigan, have invented certain new and useful Improvements in Grease Cups, of which the following is a specification.

This invention relates to improvements in 10 grease cups and especially that type employed on locomotive driving rods and in similar locations. Grease cups as ordinarily constructed and employed in this connection are unsatisfactory in use because of 15 the fact that the plug or follower and sometimes the cup itself is liable to be lost with the result that the bearings become overheated and delays are caused. It is therefore the primary object of the present invention to provide a grease cup designed 20 especially for use in the connection stated and which will embody means for preventing loss of any of its component parts regardless of the vibration to which the same may be 25 subjected.

Another object of the invention is to provide in a device of this class means for preventing retrograde movement or feeding of the plug or follower as frequently occurs in 30 the ordinary construction of grease cup and due to the vibration to which the same is subjected.

When it becomes necessary to fill the ordinary grease cup, the plug or follower is 35 bodily removed from the cup and is laid aside until grease has been packed in the cup, and during this period it is liable to drop to the road bed and thus become lost or accumulate gritty particles liable to 40 abrade and wear its threads. Therefore it is another object of the invention to assemble the plug or follower with the cup in such a manner that the plug or follower will be supported clear of the cup and yet 45 remain connected therewith while grease is being packed in the cup.

In the accompanying drawings:

Figure 1 is a view partly in vertical section and partly in elevation illustrating 50 the grease cup embodying the invention;

Figure 2 is a top plan view of the cup;

Figure 3 is a sectional view illustrating a slight modification.

In the drawings, the numeral 1 indicates 55 in general a locomotive driving rod provided

in its upper side with a recess 2 which is to receive the bottom of the cup embodying the invention and which communicates with a grease duct 3 leading to the bearing of the driving rod. The grease cup comprises a 60 body 4 which is of cylindrical form and which may be exteriorly threaded and thus secured in the recess 2 or may be snugly fitted into the recess and then welded, as indicated by the numeral 5, so as to effect 65 a permanent union between the cup and the driving rod.

The cup 4 is provided with a lid which is indicated in general by the numeral 6 and which comprises a central web portion 7 and a depending circumscribing wall 8 the lower edge of which is designed to rest squarely upon the upper edge of the wall of the cup 4 when the lid is in closed position. The lid is provided at one side with an outstanding pivot ear 9 directed downwardly and fitting between spaced pivot ears 10 upon the outer side of the cup 4 at the upper end thereof, a pivot pin 11 being secured through the ears 9 and 10, and the lid being in this manner hingedly connected with the cup so that it may assume a position close to the cup as shown in Figure 1 or may be swung upwardly and outwardly 85 upon its pivot to an open position clearing the open upper end of the cup.

In order to accommodate the plug or follower which is indicated in general by the numeral 12, the cup 4 is interiorly threaded from a point adjacent its upper end to its 90 lower end, as indicated by the numeral 13, and the web portion 7 of the lid 6 is formed in axial alignment with the cup 4, when the lid is closed, with an opening 14 the wall of which is likewise threaded, the pitch 95 and size of the thread 14 corresponding with the pitch and size of the threads 13.

The plug or follower 12 comprises a stem 15 which may be of hollow form as shown in Figure 1 or solid, as preferred, 100 and a head 16 is preferably formed integral with the lower end of the stem. The stem 15 is exteriorly threaded, as indicated by the numeral 17, and adjustably fits through the opening 14 in the web of the lid 6, and the head 16, which is concentric to the lower end of the stem and is of flat circular form, has its periphery threaded as indicated by the numeral 18 so as to adjustably fit within the bore of the cup 4. The head 16 is of 110

greater diameter than the stem so that a shoulder 19 is provided at the upper side of the head 16, and a coil spring 20 is disposed upon the stem and bears at one end 5 against this shoulder 19 and at its other end against the under side of the web portion 7 of the lid 6. At its upper or outer end the stem 15 is exteriorly squared or of polygonal form, as indicated by the numeral 10 21, so that a wrench may be applied thereto for the purpose of rotating the stem to feed it downwardly into the cup 4 and follow the grease as consumed. If desired, the upper end of the stem 15 might be provided 15 with a polygonal socket for the application of a different type of wrench.

From the above description of the invention it will be apparent that when the lid 6 is in closed position, the plug may be 20 threaded down into the cup 4, the threads of the stem and head of the plug and of the opening 14 and bore of the cup being correspondingly pitched. When it is desired to gain access to the cup for the purpose of packing it with grease, the plug is 25 to be threaded upwardly until the threads of its head 16 disengage from the threads 13 of the cup 4 whereupon the plug and lid 6 may be swung upwardly and outwardly 30 away from the upper end of the cup thus uncovering the latter. During this time however the plug is not disconnected from the cup but is securely mounted by the lid 6 and cannot become misplaced or lost. 35 After the cup has been packed with grease, the lid is again swung to closed position, whereupon the plug may be threaded down through the opening 14 and into the cup 4 and adjusted from time to time as occasion 40 may require. The lid has of course a concavity of sufficient depth in its under side to accommodate the head 16 and the compressed spring 20 when the stem is threaded

upwardly in the manner above explained to clear the threads of the cup 4. 45

Under running conditions the cup will be subjected to vibration but this will not result in a retrograde movement or feeding of the plug 12 for the reason that the spring 20 will exert a sufficient binding action between the plug and the lid 6 to lock the parts with relation to each other and therefore the plug will be maintained in any position to which it is adjusted, regardless 50 of the vibration to which it is subjected. 55

It will be observed by reference to Figure 1 that the under side of the head 16 of the plug is formed with a concavity 23 having the contour of a segment or sphere so that as the plug is threaded down into the cup, the compressed grease will be kept to the 60 center of the cup. 65

Having thus described the invention, what is claimed as new is:

In a device of the class described, a cup having a threaded bore terminating adjacent its upper end and having the upper portion of its bore smooth, a lid hingedly connected with the cup and having a threaded opening in its top, the threads of said opening being of the same pitch as the threads in the cup, and the bore of the lid being smooth, a follower having threaded engagement with the bore of the cup, a stem rising from the follower and rotatably engaged in the threaded opening in the lid; and a spring coiled around the stem between the follower and the lid in the smooth-bore portion of the lid and the cup with its ends 70 acting on the lid and the follower to resist 75 the reverse rotation of the follower and the stem. 80

In testimony whereof we affix our signatures.

ANTHONY P. LIEDER. [L. S.]
JOSEPH F. SMITH. [L. S.]
